SPARK PLUG

Edward B. Nowosielski, Bloomfield, N. J., assignor, by mesne assignments, to Bendix Aviation Corporation, South Bend, Ind., a corporation of Delaware

Application May 1, 1930, Serial No. 449,039

15 Claims. (Cl. 123—169)

This invention relates to ignition systems for internal combustion engines and more particularly to spark plugs.

One of the objects of the present invention is to provide an improved spark plug which is both mechanically and electrically strong, and is capable of long service without mechanical or electrical faults.

Another object is to provide an improved spark plug which embodies novel means for preventing the escape of gases from the engine cylinder through the spark plug structure with a consequent loss of compression.

A further object is to provide a spark plug of improved structure which embodies novel electrical shielding means for preventing interference with the operation of sensitive electrical apparatus, such as radio equipment.

A still further object is to provide a spark plug embodying a novel gas-tight seal and an improved shielding means which on account of its simplicity and small number of parts is rugged in structure, cheap to manufacture and easy to assemble.

Several embodiments of the present invention are illustrated in the accompanying drawing, but it is to be expressly understood that said drawing is for the purposes of illustration only and are not to be construed as a definition of the limits of the invention, reference being had for this purpose to the appended claims.

In the drawing:

Fig. 1 is a side elevation, partly in section, of one embodiment of the present invention;

Fig. 2 is a front elevation of the embodiment shown in Fig. 1;

Figs. 3 and 5 are side elevations, partly in section, of other embodiments of the present invention; and

Figs. 4 and 6 are sections taken on lines 4—4 and 6—6 of Figs. 3 and 5 respectively.

Referring now to the drawing, wherein like reference characters indicate like parts throughout the several views, Figs. 1 and 2 illustrate an improved spark plug which embodies novel means for forming a gas-tight seal to prevent the escape of gases through the body of the spark plug from the engine cylinder, and a novel form of electrical shield for preventing interference with other sensitive electrical apparatus. In the form shown, said plug comprises, in general, a body portion, a positive electrode and a negative electrode. Body portion 7 is exteriorly threaded as at 8 for threaded engagement with an opening in a cylinder wall of an internal combustion

engine in the usual manner. The upper part of body portion 7 is internally threaded as at 9 and is of larger diameter than the lower part so as to provide an inner shoulder 10.

5 The positive electrode comprises a metallic spindle 11 having at its lower end an enlarged head 12, which carries a spark gap point 13. An insulator 14, preferably a mica sleeve, surrounds electrode 11 practically throughout its length, resting at its lower end on head 12. A plurality of insulating washers 15, preferably of mica, surround the lower portion of electrode 11 and insulating sleeve 14 adjacent head 12, said washers also resting upon head 12 and preferably being 10 of increasing outer diameters away from said head. On top of insulating washers 15 there is seated a gland 16 externally threaded as at 17 and surrounding the intermediate portion of electrode 11 and insulating sleeve 14, but separated therefrom so as to provide a space for the insertion of packing material. Gland 16 is provided with an inclined bottom portion 18, the outer surface of which conforms in slope to shoulder 10 of body portion 7, and with an annular 15 groove 19 formed in its inner surface for purposes later to be described.

In the space thus formed between insulating sleeve 14 and gland 16, there is provided a sleeve 20 of compressible packing material, preferably 20 copper. This sleeve 20 of compressible material is forced between insulating sleeve 14 and gland 16 under great pressure by any suitable means so that groove 19 of gland 16 is completely filled with said material, and insulating sleeve 14 is 25 wedged into close engagement with electrode 11 thus forming a double gas-tight seal around the electrode.

A plurality of other insulating washers 21 are 30 provided resting on top of gland 16 and surrounding the remaining upper portion of electrode 11 and insulating sleeve 14, said washers preferably decreasing in diameter toward the top of electrode 11. Retaining head 22 is then placed 35 around the top of electrode 11 and rests upon washers 21. Retaining head 22 is provided with a countersunk bore 23 into which the top of electrode 11 is expanded by upsetting or any other suitable method, thus tightly clamping together on said electrode, between retaining head 22 and 40 bottom head 12, the assembly comprising washers 21, gland 16, sleeve 20, and washers 15.

Suitable means are provided for attaching a cable or lead to electrode 11 which, in the form shown, comprise a terminal member 24 fitted with 45 a split spring tip or terminal post 25. Terminal

member 24 is placed over and in contact with electrode 11 and retaining head 22, and is secured thereto by a spun-over flange 26 which engages a corresponding collar 27 formed on retaining head 22.

The negative electrode of the spark plug preferably comprises a substantially cupped-shape metallic thimble 28 having in its bottom a plurality of perforations 29 through one of which extends point 13 of the positive electrode 11. Electrode 28 has its rim bent outwardly so as to form a flange 30 for the purpose of engaging shoulder 10 formed in body portion 7, when the spark plug is assembled.

In assembling the spark plug, the negative electrode 28 is placed in body portion 7, flange 30 resting on shoulder 10. The positive electrode assembly as described above, is then threaded into body portion 7, the inclined bottom portion 18 of gland 16 tightly clamping flange 30 of electrode 28 between it and shoulder 10 to form a gas-tight joint at this point. If desired, flange 30 may be doubled upon itself so as to afford an extra thickness of metal at this point, thereby insuring the gas-tight integrity of the joint, and rendering it unnecessary to employ the usual gasket.

A lead or wire 31 is connected to the terminal post 25 in any suitable manner, and, as shown, is provided with a terminal ring 32 which is adapted to slip over the split terminal 25. Lead 31 is covered with suitable insulation 33 including a metal shield 34 which may be formed of woven wire, for example.

In addition to the gas sealing means embodied in this spark plug, there are also provided novel means for electrically shielding said plug so as to prevent interference with sensitive electrical apparatus such as radio equipment. In the form shown in Figs. 1 and 2, said shielding means comprises a two-piece L-shaped metallic casing, and means within the casing for insulating it from the positive electrode 11 and the end of lead 31.

A lower casing member 35 surrounds the electrode 11 approximately throughout its length and is secured to body portion 7 of the spark plug by means of an inwardly directed flange 36 which engages a circular shoulder 37 formed on body portion 7. Casing member 35 is substantially cylindrical in shape except at its upper end where there is provided a laterally extending portion 38 of substantially semi-circular cross section which surrounds the lower half of lead 31. A cap 39 is provided which cooperates with casing member 35 and closes the top of electrode 11 and lead 31. Cap 39 is also approximately semi-circular in cross section and is provided with flanges 40 which engage similar flanges 41 formed on casing member 35.

Means are provided for holding cap 39 in cooperative engagement with member 35, and, in the form shown, comprise a bail 42, pivoted in member 35 as at 43, the top of which engages a groove 44 formed in cap 39.

Suitable insulating means are provided within the above described casing, comprising, in the form shown, an upper insulator member 45, formed of porcelain or other suitable material, which is held within cap 39 and which conforms to the shape of the top of the electrode 11 and lead 31, and a lower insulator member 46 of the same material secured within casing member 35 and complementary to upper member 45. Insulator member 46 also includes a vertical portion 47 which surrounds the positive electrode assem-

bly and rests upon the top of gland 16. It will be understood that the two parts of the shielding casing may be die-cast around the insulator members, electro-deposited thereon, or formed in any other suitable manner.

In Figs. 3 and 4, there is illustrated another embodiment of the present invention. In this form, the packing material placed between the insulating sleeve 14 and gland 16 comprises a pair of wedge rings 48 and 49 of compressible material such as copper. These rings are placed between sleeve 14 and gland 16 with their inclined faces in engagement and with the base of ring 48 resting on the inclined bottom portion 18 of gland 16. Pressure is then applied, by any suitable means, to the top of ring 49, and the resultant expansion of the rings forms a double gas-tight seal around electrode 11 in a similar manner as described for sleeve 20.

The shielding casing shown in Figs. 3 and 4 differs from that of Figs. 1 and 2 in that it is divided in a vertical plane into two symmetrical halves 50 and 51, which are held together in cooperative relation by means of a clamp ring 52 having a screw 53. Clamp ring 52 is prevented from sliding off the casing when in its clamped position by means of an annular projection 54 formed on said casing. In this embodiment, engagement with body portion 7 of the spark plug is obtained by the clamping action between a flange 55 formed at the lower end of the shielding casing, and the upper circular portion of body 7.

Figs. 5 and 6 show an additional form of shielding casing, which is similar to that of Figs. 3 and 4 in that the casing is divided in a vertical plane into two symmetrical halves 56 and 57. These halves, however, are hinged together as at 58, and are connected to body portion 7 of the spark plug by means of a sleeve or ring 59 which engages shoulder 37, the casing telescoping within said ring and being secured thereto as by screws 60.

There is thus provided an improved spark plug structure which is rugged and strong both mechanically and electrically, and which is compactly and easily assembled from a small number of parts. Due to its simplicity it is also cheap to manufacture. Novel means are provided in this spark plug for effectively preventing the escape of gases from the engine cylinder, through the spark plug structure, and thus decreasing loss of compression. Also, novel shielding means are provided which totally insulate and electrically shield all portions of the spark plug which by radiation of the high tension ignition current might cause interference with sensitive electrical apparatus in the vicinity, such as radio equipment. The novel shielding means are also simple in structure, and may be quickly and easily attached to or detached from the spark plug body.

It will be obvious that the invention is not limited to the specific forms described and illustrated in the drawing, but is capable of a variety of mechanical embodiments. Various changes, which will now appear to those skilled in the art, may be made in the form, details of construction and arrangement of parts without departing from the spirit of the invention, and it will be understood that the shielding means may be employed with spark plug structures other than that illustrated. Reference is therefore to be had to the appended claims for a definition of the limits of the invention.

What is claimed is:

1. Apparatus of the class described comprising

in combination a spark plug body, a portion including an electrode extending therefrom, a cable connected to said electrode, means for housing and shielding said electrode and cable comprising an L-shaped metallic casing having insulating means therein, said means in one arm of said casing being shaped to receive said cable and in the other arm to cover the extended portion of said spark plug, said casing being formed in two parts which register, one with the other, along a plane passing through the longitudinal axis of said cable, and means for connecting said parts together.

2. Apparatus of the character described, comprising in combination, a spark plug body having a circular shoulder, an electrode extending therefrom, a cable connected to said electrode, means for shielding and housing said electrode and cable comprising a two-piece metallic elbow into one arm of which said cable extends, the other arm surrounding said electrode, means for insulating said elbow from said electrode and cable, means for holding the two said pieces of said elbow in cooperative relation along a plane passing through the longitudinal axis of said cable, and separate means for securing said elbow to said circular shoulder of the spark plug body.

3. Apparatus of the class described comprising in combination a spark plug body having a circular shoulder, an electrode extending therefrom, a cable connected to said electrode, a metallic casing having engagement with said circular shoulder and extending substantially the length of said electrode, a metallic cap cooperating with the outer extremity of said casing to enclose and shield said electrode and cable, means including a bail for securing said cap to said casing, and means for insulating said casing and cap from said electrode and cable.

4. Apparatus of the character described, comprising, in combination with a spark plug body and an electrode extending therefrom, a cable connected to said electrode, means for shielding and housing said electrode and cable comprising a two-piece metallic elbow into one arm of which said cable extends, the other arm surrounding said electrode, means including a two-piece insulator for insulating said elbow from said electrode and cable, and means for holding the two pieces of said elbow in cooperative relation along a plane passing through the longitudinal axis of said cable.

5. A shield for a spark plug and its associated cable comprising a metallic elbow constituted by a pair of sections enclosing the plug and cable, said sections being in registry along a plane passing through the longitudinal axis of the cable, and pivotally mounted means for holding said sections in registry along said plane.

6. A shield for a spark plug and its associated cable comprising a metallic elbow constituted by a pair of sections enclosing the plug and cable, said sections being in registry along a plane passing through the longitudinal axis of the cable, and means for holding said sections in registry along said plane, said means including a clamping device engaging both said sections.

7. A shield for a spark plug and its associated cable comprising a metallic elbow constituted by a pair of sections enclosing the plug and cable, said sections being in registry along a plane passing through the longitudinal axis of the cable, and pivotally mounted means for holding said sections in registry along said plane, said means including a clamping device engaging both said

sections and having its ends secured in one only of said sections.

5 8. In an engine ignition system, a shielded cable and a tubular spark plug shell, a metallic housing connecting the cable shield and tubular shell, said housing including a body of insulating material and upper and lower metal coverings joined together along mating edges and enclosing said body, in such manner that opposite ends 10 of the lower covering have conducting relationship to the cable shield and the spark plug shell respectively; said body of insulating material having a bore in line with said tubular spark plug shell, and means extending through said bore and into said tubular shell for supplying current to 15 the spark gap region of the plug.

9. In combination with a spark plug having a body portion provided with a shoulder, a metallic member surrounding said plug and having a portion 20 extending inwardly for engagement with said shoulder, a second metallic member having edge engagement with the edge of the first, and means engageable with the upper most surface of said second metallic member for securing said second metallic member in operative relationship to the first.

10. In combination with an engine cylinder, a spark plug insertable into said cylinder, a spark plug shield comprising a metallic cup having a portion in engagement with both the plug and the cylinder, a dielectric body extending into said cup, and a metallic cap extending over only the uppermost surface of said dielectric body and secured to said cup with their edges in register.

35 11. In combination with a spark plug and a radio shielded cable therefor, shielding means for the plug comprising a lower shielding member extending upwardly to a point beyond the upper end of the plug, an upper shielding member detachably connected to said lower member, and an insulating member within said shielding means, said insulating member having a skirt extending around the upper portion of the plug.

40 12. A spark plug shield of the type including a plurality of shielding parts for enclosing the plug and a dielectric body disposed between the plug and shielding parts, said dielectric body having a tubular passage for the introduction of the ignition cable, characterized by the fact that two of said shielding parts separate substantially along a plane through the longitudinal axis of said passage, and a clamp surrounds said parts for retaining the said parts in operative position.

55 13. A spark plug shield of the type including a plurality of shielding parts for enclosing the plug and a dielectric body disposed between the plug and shielding parts, said dielectric body having a tubular passage for the introduction of the ignition cable, characterized by the fact that two of said shielding parts separate substantially along a plane through the longitudinal axis of said passage.

60 14. In combination with a shielded conductor and a spark plug including a metal shell having a wrench receiving portion and a shoulder below said wrench receiving portion, a device for preventing radiation of electrical energy therefrom comprising a casing formed of complementary sections, one of which has an apertured portion for engagement with said shoulder and a portion of wider bore surrounding but spaced from said wrench receiving portion, means adapted to hold said sections in contact with each other along a plane passing through said

shielded conductor, and a dielectric body interposed between said casing and said plug.

15. In combination with a shielded conductor and a spark plug including a metal shell having a wrench receiving portion and a shoulder below said wrench receiving portion, a device for preventing radiation of electrical energy therefrom comprising a casing formed of comple-

5
mentary sections, one of which has an apertured portion for engagement with said shoulder and a portion of wider bore surrounding but spaced from said wrench receiving portion, means adapted to hold said sections in contact with each other adjacent said conductor, and a dielectric body confined by said casing sections.

EDWARD B. NOWOSIELSKI.
